UNITED STATES PATENT OFFICE.

WALTER EDWIN TRENT, OF WASHINGTON, DISTRICT OF COLUMBIA, ASSIGNOR TO TRENT PROCESS CORPORATION, OF NEW YORK, N. Y., A CORPORATION OF DELAWARE.

PROCESS FOR DISTILLING SOLID CARBONACEOUS MATERIALS.

Application filed January 11, 1923. Serial No. 612,080.

The invention relates to improvements in a process for removing volatiles from carbonaceous materials, and forming a carbonized or coked residue.

5 The invention primarily consists of a process for distilling pulverized coal, or plastic mixtures of coal and oil in which the carbonaceous fuel is placed in a retort and on a heating surface therein provided with 10 a plurality of vertically disposed heat radiating elements that are surrounded by the carbonaceous fuel to apply therein heat to all parts of the charge.

In accordance with this process, the carbonaceous fuel which may be pulverized coal, or a mixture of coal and oil, is introduced to a retort having a base and a series of upstanding heating elements projecting from said base so that the fuel has formed therein 20 a plurality of openings providing extra heating surfaces, the walls of which contact with said heating elements. The vertical heating elements, therefore, in effect, form combined mandrels and heating devices 25 whereby heat is applied to the fuel throughout its mass at a plurality of different points, causing a rapid vaporization of the fuel mass and the production of a carbonized residue.

30 The present invention contemplates a modification of the process disclosed in my Patent No. 1,591,729, dated July 6, 1926, which was copending with the present case, and in this broader aspect, provides means 35 for forming openings in the comminuted coal charge by the upstanding heating elements, eliminating the necessity of first forming in a bonded mass a plurality of flues for the passage of heat when said mass 40 is inserted in a retort in the manner disclosed in my said Patent No. 1,591,729.

In the accompanying drawings, I have shown two forms of apparatus for carrying out this process, in which Figure 1 represents a view of an electrically heated retort forming a part of a stove; and, Figure 2 is a view of a gas heated retort where the gases discharge to a collector.

45 Referring now more particularly to the drawings, wherein like reference characters indicate corresponding parts, and having specific reference to the electrically heated retort shown in Figure 1, the numeral 1 designates the body of the retort which may

or may not be lined with a refractory material. The retort has a supporting base 2 composed of insulating material upon which there is seated an electric base grid 4 provided with a plurality of upstanding heat conducting mandrels 5 which will be more 60 fully hereinafter described. The upper end of the body has attached thereto by removable bolts 6 an extension 7 being dished at its under surface and formed with a plurality of burner jets 8 adapted to extend upwardly adjacent a vessel support 9 upon which a vessel 10 is seated. These jets are controlled by valves 11 and receive gas passing from the pocket on the under side of the extension 7, which gas is generated from the 70 fuel introduced to the retort, and is burned by said jets to heat the supported pan.

As shown in Figure 1 the base grid 4 is seated on the insulating base 2 so as to be insulated from the retort and this grid is 75 connected with the electric connector 11^a at one side of the base. The grid is preferably formed with a plurality of apertures receiving the upstanding mandrel and heating elements 5. These elements are preferably of a 80 tapering form and have an external wiring 12 of resistance material connected with the source of current supplied at the connector 11^a. The resistance elements are shown as externally surrounding the heating elements, 85 but it will be understood that said elements may be internally wound or heated in any other convenient manner. The upstanding elements function to form in a mass of fuel that is introduced to the retort a plurality 90 of vertical spaces and to impart heat directly to the walls of such spaces whereby the volatiles will be rapidly vaporized, obviating the necessity of heat penetrating from the base of the retort upwardly 95 through the entire mass. These heating elements need not be wound with an electric wiring and may, if desirable, conduct heat to the walls of the space by heat conduction.

When using the apparatus for the generation of gas, comminuted coal is placed within the body 1 of the retort and tamped around the upstanding heating mandrels 5 therein. In lieu of pulverized coal I may introduce to the retort a plastic fuel consisting of finely pulverized coal and oil of a consistency resembling mortar, which fuel is produced by the process disclosed in my Pat- 100 105

ent No. 1,420,164. This fuel has been found to be highly useful, as large quantities of gas may be obtained therefrom and a high grade coke or carbon residue recovered.

5 When a fuel charge has been introduced to the retort electric current is applied to the base grid 4 and also preferably to the up-standing heating elements 5 resulting in the application of heat to the base of the charge 10 and also to the walls of the spaces or openings surrounding said heating elements 5. The heat is thereby applied throughout the mass of carbonaceous material so that the volatiles rapidly vaporize and a carbonized 15 residue forms in the retort. This heating continues until the material has been converted to a carbonized substance or coke whereupon the extension 7 is removed and the retort turned to an inverted position to 20 discharge the coke therein.

In the modification form of the invention shown in Figure 2 of the drawings I have illustrated a means for producing gases by the use of heat generated from a combustible 25 mixture and in this construction the gases produced are led off to a container and there stored for subsequent use. As disclosed in this figure the body of the retort is indicated by the character 20, the same having 30 a movable closure 21 provided with a gas outlet 22 leading to a gas storage container. A hollow base 23 is provided having baffles 24 therein, a gas inlet 25 for introducing 35 gas and air to be burned in the hollow interior of the base, the products of combustion passing out through the discharge 26. The heating base 27 is formed with a plurality of upstanding heating mandrels 28 and 29 respectively, the mandrels 28 being 40 hollow so that heating gases pass upward-ly therein, while the mandrels 29 are of a solid formation. When this apparatus is in use the movable closure 21 is removed and a supply of material which may be com- 45 minuted coal or a mixture of coal and oil is introduced to the container 20 and tamped around the upstanding mandrels 28 and 29 therein and the closure then replaced. The combustible charge admitted to the base of 50 the retort is ignited and the combustion gases heat the base 27 and the mandrels to a tem- 55 perature of say 1500° F. This results in a rapid vaporization of the volatiles in the mass, the heat being applied throughout the mass by reason of the heating mandrels 28 and 29, and these volatiles pass on through the outlet in the container 21 to a point of storage. When a coke residue has been 60 formed the closure 21 is removed and the carbonized material discharged, a supply of green material being then placed in the re- 65 tort.

As a further modification of the invention I may eliminate using the grid 4 shown in Figure 1 as a heating grid by disconnecting 65 the electric current therewith and apply all of the heat to the fuel charge through the mandrels 5. I, however, preferably apply heat to the grid, as this assists in a rapid vaporization of the volatiles.

In the accompanying drawings I have merely shown the preferred embodiments of this invention, but it will be appreciated that the retorts may be materially changed in construction, and that a series of the retorts 75 may be used if desired, without departing from this invention so long as there is provided in each retort a heating base and a plurality of upstanding heating elements 80 which serve as mandrels in each retort and to also apply heat to the walls of the openings formed by said mandrels in the fuel being treated.

In actual practice it may be desirable at 85 times to subject a charge of green fuel to its initial heat treatment by the use of electrically heated mandrels, and as distillation proceeds, to discontinue use of electric energy as a heating means and heat the mandrels by means of heating gas or the like. Such 90 a process would be more economical under certain conditions of operation.

Having thus described my invention, what I claim is:

1. A process for distilling solid carbonaceous fuels in a retort having a plurality of heating mandrels, consisting in surrounding said mandrels with the carbonaceous fuel, and in heating the mandrels to apply heat to the carbonaceous fuel to vaporize the volatiles in the charge and form a carbonized mass having therein a series of openings when removed from the retort.

2. A process of distilling solid carbonaceous fuels in a retort having a plurality of heating mandrels, consisting in supplying fuel to the retort to surround the mandrels and form in the fuel charge a plurality of separated openings, and in heating said mandrels to apply heat to said carbonaceous charge around said mandrels to vaporize the volatiles in the charge and form a carbonized fuel residue.

3. A process for distilling comminuted substantially solid carbonaceous fuels in a retort having heating mandrels, consisting in supplying said fuel to the retort to surround the mandrels, and in heating said mandrels to apply heat to the surrounding carbonaceous fuel to remove its volatiles and produce a carbonized residue.

In testimony whereof I affix my signature:

WALTER EDWIN TRENT.
